UNITED STATES PATENT OFFICE.

JAMES G. HUFFMAN, OF DECATUR, ILLINOIS, ASSIGNOR OF ONE-HALF
TO EDMUND M. HYBARGER, OF PANA, ILLINOIS.

CAR-LOADER.

No. 819,279.

Specification of Letters Patent.

Patented May 1, 1906.

Application filed July 3, 1905. Serial No. 268,249.

To all whom it may concern:

Be it known that I, JAMES G. HUFFMAN, of the city of Decatur, county of Macon, and State of Illinois, have invented certain new and useful Improvements in Car-Loaders, of which the following is a specification.

This invention relates to means for loading cars with grain and the like. The general mode of operation is to force the grain into the cars by a blast of air, and a primary object of the invention is to feed the grain mechanically into the air-blast and to hold the grain against back motion.

Another object is to provide for properly distributing the grain in the car.

Another object is to provide for escape of dust from the current of grain and air, and further objects relate to details of construction with a view to general improvement of the loader.

In the drawings forming part of this specification the essential features of the invention have been illustrated in the construction thought to be most available and non-essentials have been in part omitted.

In Figure 1 the exterior of the loader has been shown in side elevation. Fig. 2 is a front elevation of the loader as it appears when not in use. Fig. 3 is a central vertical section through the operative parts of the loader. Fig. 4 is a section on line X in Fig. 3. Fig. 5 is a central vertical section through the compound distributing conveyer or chute. Fig. 6 is a plan of the discharge end of the loader and the distributing-chute, showing the chute in operative position. Fig. 7 is an end view of a chute, showing how the tube is preferably flattened.

A grain-feeding compartment is shown at 1. A fan-casing is shown at 2, and at 3 is shown the discharge end of the grain-feeding compartment through which the grain is forced by the blast of air.

The opening through which grain passes to compartment 1 is shown at 4. At 5 is shown a horizontal shaft which extends lengthwise of compartment 1 and carries the spiral conveyer 6, and a cylindrical casing 7 encircles the greater part of the conveyer. A slot 8 is formed in the lower part of casing 7 at the discharge end thereof. An inclined chute 9 is formed beneath slot 8, and a slide-valve 10, controlled by rod 11, provides means for closing slot 8 more or less completely. The

discharge end 3 of the compartment 1 is inclined downwardly to direct the grain properly, and it is provided with a diverting-plate or partition which may be swung to one side or the other by means of rod 43 in order to divert the grain toward either of the two side-wise-extending chutes used to discharge the grain into a car.

The partition or diverting-plate is shown at 12, and its upper edge is preferably held in position between the two parts of which nose 3 is formed. The casing 7 is cut away at 13 at its outer end and near its upper surface, and the upper wall of compartment 1 is also cut away to form passages for dust, as shown in Fig. 4. A passage-way 14 is formed on the upper surface of compartment 1 in communication with the dust-passages 13 through casing 7, and a valve 15 provides means for controlling the escape of dust. A bracket 16 depends from the upper surface of casing 7 and forms a bearing for one end of shaft 5. A wall 17 coacts with the under surface of the casing 7 to form the air-passage 18, leading from the fan. The fan 19 is preferably supplied with blades 20 and 21, shaped as shown in Fig. 3, and it is mounted on shaft 22.

Grain passing from compartment 1 through nose 3 is delivered to the trunk or hopper 24 and forced therefrom through the chutes 25 and 42. A flap 37 on hopper 24 is hinged on rod 23 and the rod extends through lugs on the discharge end of compartment 1. Flanges 38 are adapted to fit around the part 3 of compartment 1 when the discharge-chutes are raised to the position shown by broken lines in Fig. 1, and a notched bar 26 provides means for holding the chutes in their raised position. The bar 26 has a bail 26^a, which is pivotally connected with the chutes, and it is notched at 27 to engage the bracket 28 when the chutes are raised. Two principal chutes, each designated by 25, extend side-wise in opposite directions from the trunk or hopper 24, and a third chute 42 extends directly forward midway between chutes 25. The central chute is smaller than the others, and it has a mouth 42^a inside the hopper, which is adapted to coincide, approximately, with the discharge end of the inclined chute 9 when the chutes are raised. A valve 41 in chute 42 provides means for closing the chute to a greater or less extent, and this valve may be constructed in any desired manner. In

this instance the valve is shown hinged to a side of the chute and a set-screw 40 is screwed through a fixed nut 39 to adjust the valve.

It is a matter of mechanical construction 5 to provide means for driving the different parts of the machine, and different environments may demand different constructions. I prefer, however, to provide shaft 5 with a pair of sprocket-wheels of different sizes, as 10 29 and 30, to mount sprocket-wheels 31 and 32 loosely on a counter-shaft 33, to connect wheels 29 and 30 with wheels 31 and 32 by means of chains 35 and 36, and to use a shiftable clutch-collar 34 to engage one or the 15 other of the sprocket-wheels 31 or 32. When oats is to be loaded, shaft 5 is driven through chain 35, and when the machine is used to load corn the clutch-collar is shifted into engagement with wheel 32 and shaft 5 is driven 20 slower through chain 36.

The loader usually stands alongside a track with its conveyer-chutes hanging down, as shown in Fig. 1 in solid lines. The car to be loaded is run alongside the elevator 25 with which the loader is connected, the chutes 25, 25, and 42 are swung upward into the door of the car and held there by brace-bar 26, and the curved chute-sections 44 are placed one on each of the conveyer-tubes 25, 30 as shown in Fig. 6. When the machine is started, the grain to be loaded is fed by gravity into the mouth 4 of compartment 1 and is forced by the spiral conveyer 6 through casing 7 while a blast of air is developed by 35 the fan and directed in the directions indicated by arrows in Fig. 1. The heavier grains settle to the bottom of the casing 7 and fall into the inclined chute 9 through slot 8, while the remainder is forced over the 40 tail of the casing and into the trunk 24 of the conveyer-chutes. The grain passing through chute 9 is discharged into conveyer-tube 42, and the remainder is divided into two streams, one of which is discharged to the 45 right through one of the conveyer-tubes 25, while the other is discharged to the left through the other tube. The quantity of grain delivered to each tube 25 may be varied somewhat by the adjustable partition or deflector 12. The curved sections 44 are rotatable on tubes 25, and the rods 45 act as handles to permit the curved sections to be suitably manipulated. By turning the curved sections into different positions the grain 55 may be discharged properly into different parts of the car. As a matter of preference, the curved sections 44 are flattened in cross-section, as shown in Fig. 7, so that a broader surface of grain may be exposed to the action 60 of the air-blast and the grain be thereby more effectively and completely discharged. The tubes 25 of the discharge-chute are straight throughout their lengths and the curved sections 44 are also straight where 65 they telescope on tubes 25 to permit rotary

adjustment. The curved extensions of sections 44 are broadened sidewise, as shown in Fig. 7. As the grain is fed into the air-blast by the conveyer 6 it completely prevents back action of the blast by closing the grain-passage, and whatever back action the resistance of the grain may develop in the air-blast is used or may be used to carry dust through openings 13.

The invention is exemplified in the structure hereinbefore described, although it is not of necessity confined to this precise structure, and it is defined in the appended claims.

Having thus described my invention, I claim as new and desire to secure by Letters Patent—

1. In a car-loader, the combination of an air-passage, means for producing a blast in the air-passage, a cylindrical grain-passage above the air-passage, a slot in the discharge 85 end of the lower part of the grain-passage, an inclined chute extending below the slot and into the air-passage, and a screw conveyer in the grain-passage.

2. In a car-loader, the combination of an 90 air-passage, means for producing a blast in the air-passage, a cylindrical grain-passage above the air-passage, a slot in the lower part of the discharge end of the grain-passage, a slide to limit the length of the slot-opening, 95 an inclined chute extending below the slot and into the air-passage, and a screw conveyer in the grain-passage.

3. In a car-loader, the combination of a cylindrical grain-passage, a screw conveyer 100 in the grain-passage, conveyer-chutes attached to the discharge end of the grain-passage in which the screw operates, dust-outlets in the cylindrical grain-passage above the discharge end of the screw, an air-passage 105 beneath the grain-cylinder and communicating therewith at the discharge end thereof, and a fan to produce a blast in the air-passage.

4. In a car-loader, the combination of a 110 cylindrical grain-passage, a screw conveyer in the grain-passage, an air-passage beneath the grain-passage communicating therewith at the discharge end thereof, a slot in the lower part of the discharge end of the cylindrical grain-passage, an inclined chute beneath the slot and in the air-passage and a three-part conveyer-chute having the central member adapted to receive grain from the inclined chute beneath the slot of the 115 grain-passage.

5. In a car-loader, the combination with a grain-passage and an air-passage communicating therewith, of a trunk, or hopper placed to receive the combined blast of air and grain, a pair of diverging conveyer-tubes to receive grain from the upper part of the trunk and a central conveyer-tube to receive grain from the lower part of the trunk.

6. In a car-loader, the combination with a 130

grain-feeder and an air-blast, of a trunk or hopper to receive the grain forced by the blast, a pair of divergent conveyer-tubes attached to the hopper, a central conveyer-tube secured to the hopper and a valve in the central tube.

5 7. In a car-loader, the combination with a grain-feeder and an air-blast of a trunk or hopper hinged to the discharge end of the grain-feeder and provided with a plurality of conveyer-tubes and a notched brace hinged to the hopper and adapted to hold the tubes in a raised position.

10 8. In a car-loader, the combination of a grain-passage, a screw in the grain-passage, a grain-deflecting plate swung from its upper edge in the grain-passage beyond the screw,

an adjustable cross-rod connecting with the lower part of the deflecting-plate, an air-passage communicating with the grain-passage 20 in front of the deflecting-plate, and a fan to produce a blast in the air-passage.

9. In a car-loader, the combination of a screw conveyer, a casing for the conveyer having a nose protruding beyond the screw, 25 and a discharge-chute hinged to the under part of the nose and adapted to form a continuation of the nose when raised.

In testimony whereof I sign my name in the presence of two subscribing witnesses. 30
